CLAIM

The ornamental design for an adjustable P-clamp, as shown and described.

DESCRIPTION

FIG. 1 is a perspective view of a first embodiment;
FIG. 2 is a front elevation view thereof;

FIG. 3 is a back elevation view thereof;

FIG. 4 is a top plan view thereof;

FIG. 5 is a bottom plan view thereof;

FIG. 6 is a left elevation view thereof; and,

FIG. 7 is a right elevation view thereof.

The broken away symbols indicate that any portion of the adjustable P-clamp beyond what is shown forms no part of the claimed design.

The broken lines show portions of the adjustable P-clamp that form no part of the claimed design.

1 Claim, 2 Drawing Sheets(56)
